MACHINE GUN MOUNT AND SHOCK ABSORBER

August A. Danielsen, Rosedale, and Armand P. Schleret, Babylon, N. Y., assignors, by mesne assignments, to General Bronze Corporation, Garden City, N. Y., a corporation of New York

Application May 8, 1944, Serial No. 534,596

5 Claims. (Cl. 89—44)

1

This invention relates to a machine gun mount and to a shock absorber, snubber and accelerator.

An object of the invention resides in the provision of a twin machine gun mount that is particularly adapted for heavy barrel guns, which will insure true and continuous firing of both guns for a great number of rounds.

A further object of the invention resides in the provision of a machine gun mount that is so constructed that the "labor" of the gun during its reciprocations on recoil and counterrecoil will greatly be reduced, with the result that the periods between automatic firings will be reduced to such an extent that the number of rounds fired by the gun per minute will greatly be increased, and with the further result that the power of the gun to lift ammunition also will greatly be increased.

A still further object of the invention resides in so constructing the mount that the gun or guns may readily be removed therefrom without necessitating the removal of the gun handles, and also in the provision of an adjustable counterbalance which may be adjusted to meet various existent conditions, which will counterbalance the gun or guns as their angles of elevation or depression are varied, and which will act to maintain the gun or guns in their various positions after movement into such positions.

It is also an object of the invention to provide means for absorbing and snubbing the shocks of recoil and counterrecoil and for accelerating the firing of successive rounds of ammunition.

Another object of the invention resides in so constructing the mount that it is adapted for rear or spade trigger firing, as well as for side trigger firing.

It is still a further object of the invention to provide a shock absorber and snubber that is adapted for, and capable of, use with reciprocating elements such as machine elements, whose reciprocations are to be gradually arrested, and to so construct the device that it will be operable in compression as well as suspension.

In the drawings:

Figure 1 is a top plan view partly in section of a twin machine gun mount constructed in accordance with our invention;

Figure 2 is a side elevation thereof;

Figure 3 is a rear elevation;

Figure 4 is a vertical longitudinal section on line 4—4 of Figure 1, a portion thereof following the vertical planes indicated by lines 4'—4' in Figure 6;

Figure 5 is a vertical longitudinal section on

2

line 5—5 of Figure 1, it being understood that a section on line 5'—5' of Figure 1 would be the same except that the fire safety control would not appear therein;

5 Figure 6 is a transverse vertical section on line 6—6 of Figure 1;

Figure 7 is a transverse vertical section on line 7—7 of Figure 1;

10 Figure 8 is a horizontal longitudinal section on line 8—8 of Figure 5;

Figure 9 is a horizontal longitudinal section on line 9—9 of Figure 2;

Figure 10 is a detail sectional view of a portion of the fire control mechanism; and

15 Figure 11 is a detail of the lateral adjusting mechanism which is associated with the traversing mechanism and the rear of the receiver.

In the drawings (see Figures 1, 2, 3, 4, 5, 6 and 7) is shown the twin guns in dotted lines to show their relationship with the carriage and yet not to obscure the carriage itself.

Referring now to the embodiment of the invention illustrated in the drawings, the details of which are selected for illustrative purposes, the 25 twin guns 10 are shown in dotted lines, it being understood that when mounted in the carriage, one is mounted in each of the two cradles 11 and 12, each gun being mounted for removal independently of the other. The two cradles are rigid with each other, being connected together, for instance, at 11' and 12'. This carriage is pivotally mounted at 13 on a pintle fork which includes two elements 14 on opposite sides of the cradles and two elements 14' between the cradles. This fork is supported by the pintle 15 in the usual manner. The cradles 11 and 12 are held rigid with the pintle fork or are permitted to have pivotal movement thereon by locking pins 16. The cradle mounting is as follows:

40 A rear traversing mechanism secures each gun receiver to the rear of the carriage in such manner that the gun is capable of having longitudinal rectilinear reciprocations on the carriage. A slide 17, which has dovetailed engagement at 18 with a bearing plate 19 that is removably secured to the bottom 20 of each cradle 11 and 12, pivotally carries the adjacent gun receiver on a pin 21. This pin 21 extends through keyhole openings 22 in the slide 17, and is provided with a complementally formed key 23.

45 Thus, the receiver of the gun is held to the traversing mechanism by the pin 21.

In order that the receiver may be adjusted laterally within the cradle and locked in its adjusted position there is provided a cam mecha-

50

nism 21', by means of which the traversing mechanism may be shifted laterally and locked in its various adjusted positions (see Figures 6 and 11). This cam 21' is mounted on the bolt 19' and is arranged within an opening in a plate 22' which is secured to the cradle 12 by bolts 23' and is held in its adjusted positions by a set screw 24'. Upon rotation of this cam the receiver of the gun will be adjusted laterally in respect of the cradle and after adjustment will be securely held in its adjusted position by the set screw 24'. A similar construction is provided in connection with the cradle 11.

As is usual, the pin 21 may be removed longitudinally after turning the key 23 into alignment with the keyhole openings 22 by means such as a handle 24. However, it normally is locked in its supporting position by locking the handle 24 against rotation by a clip as is indicated at 25 (Figure 2). The forward end of each cradle 11 and 12 is provided with an elevating mechanism for the purpose of aligning the longitudinal axes of the guns. This mechanism includes a U-shaped adapter 26 that is supported by a base 27 between which and the adapter, spacers 28 extend, which spacers are rigid with the adapter and the base. The base 27 is mounted for reciprocation in the guideways 29 which are held rigidly to the bottom of the cradle, which at this point forms an absorber housing 31, by an adjustable bolt and nut 30 which will permit the pivotal adjustment of the guide to properly align it with the rear traversing mechanism and the gun receiver, and will prevent the adapter 26 from having rocking movement longitudinally of the carriage.

Thus the receiver and the gun barrel that it carries are supported for reciprocation within the cradle at both its forward and rear ends. The forward end of the receiver (and of the gun barrel) is adjustable upwardly and downwardly away from or toward the bottom of the cradle, so that the longitudinal axis of the twin guns may be aligned, by eccentric bearings 32 (Figure 5), through which the pin 33 extends and which bearings are secured in their adjusted positions by a screw operated clamp 37'.

It is to be understood that the construction of both of the cradles is as we have described above and we have therefore described but one.

In order that the recoil and counterrecoil of the gun may be controlled in such manner that the objects and effects that have heretofore been pointed out may be accomplished, there is secured to an adapter bolt 34 that extends between and is connected with the base 27 and the adapter 26, a plunger 35 that is wedge-shaped on its ends as at 36 and 37. This means is shown in Figures 5, 7 and 8, Figure 5 being a vertical longitudinal section, Figure 7 a vertical transverse section and Figure 8 a horizontal longitudinal section thereof. The adapter bolt has a moving fit with the plunger 35 so that the plunger may pivot on the bolt. This plunger is, of course, reciprocable with the gun receiver in one direction during the recoil and in the opposite direction during the counterrecoil, and therefore resistance applied to this plunger during these two movements will control the reciprocations of the gun.

In order that this control may be exercised there is provided retarder means for each gun with which means each of the wedge shaped ends 36 and 37 of the plunger cooperates.

Each retarder includes a plurality of eccen-

trically arranged C-springs 38, 39 and 40 which rest upon the bottom 41 of the housing 31 (which is rigid with the adjacent cradle) and are loosely positioned by a rigidly mounted post 42 in the housing. The opposite end of the housing is provided with similar C-springs 38', 39', and 40', which rest upon the bottom 41 of the housing, but may have a different positioning means. This means is illustrated as including a rigidly mounted post 43 and pin 44 between which post and the innermost spring 40' the springs 45 are arranged. These springs 45 normally tend to move the C-springs 38', 39' and 40' away from the plunger 35, but this movement is limited and the positions of these C-springs are controlled by relatively adjustable cooperating wedges 46 and 47. The transverse adjustments of these wedges are made by means of an adjusting screw 48. The wedges act as a base for the C-springs 38', 39' and 40' and the springs will be held against the adjacent wedge 47 under the influence of the springs 45.

In the inactive position of the plunger 35 the walls of the wedge-shaped ends 36 and 37 will contact the adjacent ends of the C-springs 40 and 40', each of which is of less resistance than the next adjacent C-springs 39 or 39' which in turn are of less resistance than the C-springs 38 or 38'. The graduated resistance to the movements of the plunger 35 may be accomplished in many ways, but we have shown it as accomplished by means of springs and by making the springs of greater thicknesses.

It is, of course, to be understood that the C-springs of both sets may be put under initial and various compressions by means of the adjusting wedges or otherwise, even to the extent that springs 38 and 38' will be put under such compression that the stroke of the plunger 35 and consequently the magnitude of recoil and counter-recoil may be controlled.

When only the springs 40 and 40' are placed under initial compression and while the plunger is in this inactive position, the ends of the C-springs 38 and 38' will be slightly spaced from the adjacent faces of the wedge-shaped ends 36 and 37 of this plunger 35 and the ends of the C-springs 39 and 39' will be spaced from the adjacent faces of the wedge-shaped ends 36 and 37 of the plunger a slightly less distance.

As the plunger 35 moves, as the result of the recoil or counterrecoil, the wedge shaped ends 36 or 37, as the case may be, will separate the ends of the adjacent C-springs 40 or 40' against their resistance and will, after sufficient travel, contact the ends of the next adjacent C-springs 39 and 39', and meeting the resistance of these springs and operating against the same, will increasingly separate the ends thereof as the plunger continues its movement. Upon the further movement of the plunger the next C-springs 38 or 38' will be engaged and, meeting the resistance of these springs and operating against it, will increasingly separate the ends thereof as the plunger continues its movement.

Thus the movement upon both recoil or counter-recoil of the gun will be cushioned and ultimately arrested by a series of elements (there are shown and described three C-springs, but a greater or lesser number may be used or the retarder may take other forms) for successively and gradually increasing the resistance to take care of variable dynamic impact loads.

It will be realized that when the adjustable wedges 46 and 47 are used, the position of the

springs 38', 39' and 40' will be shifted in respect of the housing in which they are mounted while the positions of the C-springs 38, 39 and 40 will not be so shifted. However, the two sets of springs will bear the same relation to the plunger in any of the adjusted positions of the springs, because the plunger (and the gun receiver by which it is carried) will be shifted simultaneously in its traversing mechanism.

In other words, regardless of the adjustment of the C-springs 38', 39' and 40', this set of springs and their counterpart 38, 39 and 40 will always exert, either initially or during the reciprocating action of the gun, equal forces on the plunger.

It is of course to be understood that the resistance of the elements of each retarder may be varied to vary the effective operation of one retarder in respect of the other, or the effective operation of one retarder element in relation to the corresponding element of the other retarder may be varied.

It is here pointed out that after one set of springs or retarder elements or any thereof have been put under compression by the movement of the plunger 35 they will exert a reactant force on the plunger with the result that, when the shock absorber is used on a gun having recoil and counter recoil, the period of rest between the changes of direction of motion of the plunger 35 will greatly be shortened. This will result in an increase of the number of rounds fired per minute and also of a conservation of the available power developed by the gun during recoil and counter recoil that may be converted into lifting power, that is to say, the lifting of an increased number of rounds of ammunition per minute to the gun. Thus the device not only acts as a shock absorber and snubber, but also actually as an acceleration and a power conservator.

Referring to Figure 8, when the wedge shaped end 37 of the plunger 35 is at the end of its stroke to the right, for instance, the three springs 38', 39' and 40' will all be exerting pressure on the faces of the tapered end of the plunger. The plunger at this time being at the end of its movement and the opposite end of the plunger being free of any pressure of the springs 38, 39 and 40, the springs 38', 39' and 40' will coact with the inclined faces of the end 37 of the plunger to exert a force to assist in the initiation of the movement of the plunger in the opposite direction. When the plunger moves in the opposite direction the springs 38, 39 and 40 will similarly cooperate. Thus the period of rest at the end of each movement of reciprocation will be shortened and the action of the gun accelerated.

Moreover, regardless of the use to which the shock absorber is put, at the end of the movement against one of the retarders these springs tend gradually to urge the plunger and the element to which it is connected in the opposite direction and thus will greatly shorten the period of rest between reciprocations as has been heretofore pointed out in connection with a gun mount.

In actual operation guns mounted in accordance with the description heretofore given exhibit a greatly increased lifting power and a greatly increased number of rounds fired per minute, and when twin guns have been used, the guns have continuously operated without "stoppage" of the firing of either gun for a great period of time and a great number of rounds.

In twin mounted guns having either side trigger or rear spade firing, the trigger mechanism of each gun must alternately successively operate to have uninterrupted firing by both of the guns.

5 If one gun fires and the other gun lags, the former is apt to fire again before the firing of the second gun, and thereafter the latter will remain in a condition of "stoppage," so that the firing of both must again be initiated by ceasing the firing of the gun that is operating and again setting the firing mechanism of both guns into operation.

10 This action is brought about, ordinarily, by one gun firing and completing its movement, again, to firing position and again firing before the other gun, having fired, again returns to its firing position and is fired.

15 With our construction it has been found that when firing thousands of rounds of ammunition no "stoppage" of either gun occurs.

20 In order that the twin guns may be balanced as their muzzles are elevated or depressed an initially adjustable and automatically variable counterbalance is provided. This mechanism (Figures 4-9) includes a trunnion pin 49 which 25 is angular in cross section, which pin extends between the inner side walls 50 of the cradles 11 and 12 through complementally shaped openings and also extends through rotatable bearings 51 carried by the pintle fork portions 14'. A drum 30 52 is rigid with the trunnion pin 49 and rotatably carries a revolvable adjusting drum 53. One end 54 of a coil spring 55 is secured to the adjusting drum 53 and the other end is secured at 56 to the drum 52.

35 The face of the drum 53 is provided with a series of adjusting tool receiving openings 57, by means of which the drum 53 may be rotated in relation to the drum 52 to lessen or increase the normal tension of the spring 55. In order that 40 the spring may be kept under its normal or adjusted tension, so that it may respond to the pivotal movements of the cradles, one of the pintle fork portions 14' carries a set screw or screws 58 that are adapted to be selectively engaged with threaded openings 59 in the face of the drum 53 in the various positions of adjustment of the drum and various conditions of tension of the spring 55. Thus the weight of the guns and carriage will be counterbalanced at various points in and during their movements about the pivot 13, and any degree of resistance within limits may be predetermined.

45 The entire counterbalance mechanism is enclosed in a two-part housing having a body portion 60 and a hinged cover 61 which may be swung out of position during the adjustment of the spring 55.

50 The side firing mechanism of this invention is indicated in Figures 1, 4 and 6 of the drawings. It is constructed as follows:

55 60 The cylinder 62 is fixedly mounted on the cradles at 63 and is provided with end walls 64 and 65. Two slides 66 and 67 of lesser length than the cylinder 62 are slidably mounted in the cylinder and have surface contact therewith. These slides are provided with end walls 68 and 69 adjacent one end of the cylinder 62. Rods 72 and 73 slidably pass through the end walls 64 and 65 of the cylinder 62 and the opposite end walls 68, 69, 70 and 71 of the two slides 66 and 67, and are attached to connectors 74 for a purpose later to be described. These rods 72 and 73 carry adjusting nuts 75 which bear against spacing collars 76 that surround the rods 72 and

70 75 73 and, at their other ends, bear against the ad-

adjacent wall 70 and 71 of the slides 66 and 67 and are slidably mounted on the rods. Interposed between the walls 68 and 70 of the slide 66 is a relatively heavy spring 77. A similar spring 78 is interposed between the walls 69 and 71 of the slide 67. These springs surround the rods 72 and 73 and at one end the spring 77 bears against the wall 70 of the slide 66 and at the other end against a collar 79 which is fixed to the rod 73. The other spring 78 is similarly mounted in relation to the rod 72 and the slide 67.

The slide 66 carries a trigger actuating lug 80 and the slide 67 carries a similar trigger actuating lug 81, which lugs extend through suitable slots within the cylinder 62 so that they may have movement longitudinally thereof. Additionally relatively light springs 82 and 83 are located within the cylinder 62, and each of these springs seats against a collar 84 which is adjustable in relation to the end wall 68 or 69 of the slide 66 or 67, by means of an adjusting screw 85. The opposite ends of the springs extend through openings 86 in the end walls 70 and 71 in the slides 66 and 67, and seat against the end wall 65 of the cylinder 62.

Each connector 74 is pivotally attached to a link 87 which in turn is pivotally connected at 88 to the end of a coordinating and actuating lever 89 which is pivoted at 90 between the side walls of the cradles 11 and 12. The lower end of each of these levers 89 projects into the path of movement of an arm 91 which is rigidly carried by a shaft 92. This shaft 92 is mounted within a tubular housing 93 which is supported on the rear end of the carriage by a bracket 94 against rotation. On the end of the shaft 92 a removable firing handle 95 is secured by means of which the shaft 92 may be rotated.

The shaft 92 is mounted for rotation in bearings 96 and is maintained against longitudinal movements by a key 97. A coil spring 98, which is anchored at one end to the stationary bearing 96, is anchored at its other end to the arm 91 which is positioned by rotatable spacer collar 99 of the housing 93. This spring tends to return the arms 91 to a non-firing position, that is to say, to a position out of contact with the lever 89 and will accomplish this result when the firing handle 95 is released.

When it is desired to initiate firing, the shaft 92 is rotated in a clockwise direction (looking at Figure 4) until the roller 100 on the end of each arm 91 engages and moves the lower end of the corresponding lever 89 about the pivot 90. This movement moves the upwardly extending arm of each lever rearwardly (in Figure 4) and pulls the connecting links 87 rearwardly simultaneously. The rearward movement of these links, through the connectors 74 and the rods 72 and 73 and the springs 77 and 78, moves the slides 66 and 67 rearwardly within the cylinder 62, which slides carry with them the trigger firing lugs 80 and 81. These springs 77 and 78, being placed under desired compression by the nuts 75 in the manner which we have heretofore described, are placed under further compression when the lugs 80 and 81 engage and actuate the triggers of the firing mechanisms. Then, when the firing occurs, the rods 72 and 73, being maintained constantly in the same position under tension applied to the handle 95, the force of the counterrecoil against the lugs 80 and 81 is absorbed by the springs 77 and 78 by the reserve compression resident in these springs.

During the counter recoil the lugs 80 and 81 necessarily move forwardly to some extent but in-

sufficiently to allow the trigger to move into an uncocked position so that after the counterrecoil the lugs 80 and 81 still maintain the triggers in firing position so that the next firing will be automatic.

The springs 82 and 83, which have been described as being under compression, and as lighter than the springs 77 and 78, serve to move the slides 66 and 67, which carry the firing lugs 80 and 81 forwardly to a pre-firing position, so that when the handle 95 is rotated to a non-firing position the lugs will assume a pre-firing position and firing will cease.

Additionally the action of the springs 77 and 78 supplements the action of the spring 98 to return the links 87, the levers 89 and the arms 91 to their pre-firing positions, as well as cushioning the action of the lugs 80 and 81.

In order that the mechanism may be adapted for rear or spade firing, we have mounted a pair of rollers 101 pivotally at 102 on a bracket 103, which bracket is removably mounted at 104 on the carriage. These rollers 101, mounted on lever arm 105, are connected to each of the levers 89 by links 106 at 89'. The rollers normally lie above and out of contact with the firing spade 107 (which is indicated in dotted lines and whose connection to the firing mechanism is not shown in this drawing because it is a well known construction and is part of the gun itself).

When the levers 89 are rotated about their pivot 90 in the manner which has already been described, the links 106 will draw the rollers 101 downwardly about their pivot until they contact with, and depress, the spade to initiate and maintain the firing of the gun. It is to be understood, however, that usually both side trigger firing and spade firing are not simultaneously used, but the provision that is made for both side trigger firing and rear or spade firing makes it possible to use the mechanism of our invention in connection with either firing. This is particularly valuable because it makes the mechanism adaptable to guns having either type of firing mechanism.

If spade firing is desired, the side firing mechanism may remain intact and connected as hereinbefore described. However, when this condition is desired, the following is employed: A plate 108 is freely slidably and adjustably mounted in the cylinder 62 between the end wall 65 thereof and the adjacent ends of the slides 66 and 67. This plate may be adjusted from the position just described by an adjusting screw 109 which is in threaded engagement with the end wall of the cylinder into a position where it will engage the adjacent ends 70 and 71 of the slides 66 and 67 and lock the slides in forward positions against movements, for a purpose later to be described.

In order that the operation of firing handle 95 may be controlled, that is to say, may be locked against movement, or released so the firing may be initiated, there is provided a locking pin 110, which projects through a support 111 and the housing 93, and is provided with a hill and dale which cooperates with a complementary hill and dale of the shaft 92 to lock the shaft against rotation or to unlock it to permit rotation. To this pin 110 is secured an operating handle 112 cooperating with an indicator 113, the handle being held in its various positions of adjustment by a spring latch 114.

It is often desirable to remove a gun, such as the one with which we are here concerned, from the cradle for various reasons as for instance if the gun mount has become destroyed or distorted

so that it will no longer properly operate. When removed it is of course desirable to have the gun handles in place so that the gun may be operated from an improvised mount.

The mechanism of this invention is so arranged that the handles, which are standard on this type of gun, may remain on the gun and will not interfere with or make inconvenient the operation of the mechanism or with the placing or removal of the gun. This is evident from an inspection of Figures 1, 2, 3, 4 and 5 of the drawings, because in those figures the positions of the handles in respect of the guns and the mechanism of this invention are illustrated clearly in dotted lines.

While the above description is believed to set forth the entire mechanism and operations, the following is given as a general résumé:

When the two guns are placed in their cradle the placing of the mechanism of this invention will make it unnecessary for the removal of the handles of the guns and so the guns may be emplaced or removed with their handles in place, which will make it possible to remove the guns as desired and set them up and quickly use them on an improvised mount.

When each gun receiver is locked to the traversing mechanism and to the adapter bolt the guns may be adjusted to align their longitudinal axes both in vertical and horizontal planes by the adjustment of the cam device of the traversing mechanism and the adjustment of the eccentric bearings 32. As this adjustment is accomplished the plunger 35, being pivotally movable on the adapter bolt 34, swings into proper alignment with the axis of the gun with which it is associated.

After the counterbalance spring 55 has been put under the proper tension for the particular guns that are mounted in the manner which has heretofore been described, the carriage and the guns may be moved pivotally to depress or elevate the muzzles of the gun barrels and in the various positions of elevation or depression the guns will be maintained in such positions by the counterbalance spring 55 because of the automatically variable effectiveness of this spring as the angle of inclination of the guns changes.

Of course the horizontal movement of the guns and carriages is about the support 15.

When the guns reciprocate in the cradles under the influence of the developed forces of recoil and counterrecoil the adapter bolts 34, which are rigid with the receiver, move forwardly and rearwardly with the guns. As each gun so moves the compressing spring 40 or 40', which is under some initial tension and contacts with the adjacent wedge-shaped end of the plunger 35, resists and tends to absorb the movement of the gun because of the spreading action exerted on the spring by the moving plunger. As the moving plunger contacts the next adjacent spring 39 or 39', which is of greater resistance and whose ends are normally spaced from the adjacent wedge-shaped end of the plunger, the ends of this spring are spread and thus the resistance of this spring is added to the resistance of the already spread springs and the movement of the gun is further arrested.

A similar action takes place upon the continued movement of the gun by the contacting of and spreading of the springs 38 or 38', depending upon the direction of movement of the gun. At the end of the movement of the gun in one direction the combined counteracting forces of the three springs exert a counterpres-

sure on the plunger and tend, because of the wedge-shaped end of the plunger with which they contact, to move the plunger in the opposite direction and of course to move the gun in the opposite direction. This action of the retarder shortens the period of rest between the reciprocations in opposite directions and assists in the initiation of the movement in the opposite direction, thus overcoming the lag or labor of the gun to a material extent.

Of course the opposite retarder, when the gun is moving in the opposite direction, has a similar action.

As has been pointed out, the resistant force of each of the two opposite retarders in either of the combined shock absorbers and accelerators may be equal. However, should it be desirable the resistance of one retarder may be less or greater than that of its opponent, a condition which may be predetermined. However, the resistance of the retarders against the movements of the gun or guns may be increased or decreased by the wedge adjustment which has heretofore been described, and in so increasing the increase of resistance on one retarder will be proportionate to that on its opponent because the movement of the retarder adjacent the wedge adjustment moves the plunger 35 and the gun bodily in the traversing mechanism.

The conservation of the energy developed by the gun during recoil or counterrecoil, because of the action of the shock absorber and accelerator, makes it possible to use this energy to raise a greater number of rounds of ammunition to the gun.

When the gun is operating on side firing mechanism the links 106 are disconnected to render inoperative the spade actuating rollers 101. Thus when the fire control handle 95 is actuated to rotate the shaft 92 and the levers 89 are moved about their pivot 90 by the arms 91, the drawing rearwardly of the connecting links 87 will draw the rods 72 and 73 rearwardly against the action of the springs 77 and 78, with the result that the lugs 80 and 81 on the side firing mechanism will contact with the side triggers of the gun, and the springs 77 and 78 will be put under further compression as the triggers are drawn to their firing position. Then on the counter recoil of the gun the shock on the trigger will be cushioned by the springs 77 and 78, but as long as the firing control handle is held in its firing position the guns will continue to fire and it is to be noted that the two springs 77 and 78 are independently operable, so that each has its individual action on the lug 80 or 81 and on the associated trigger.

The lower springs 82 and 83 normally urge the slides 66 and 67 forwardly and the firing lugs 80 and 81 into non-firing and pre-firing positions.

When spade firing is desired, the links 106 are connected between the levers 89 and the levers 105 on which the firing rollers 101 are mounted and the screw 109 may be adjusted to move the plate 108 into contact with the rear edges of the slides 66 and 67 to move them into their forward positions and maintain them in such positions where the lugs 80 and 81 are in pre-firing or non-firing positions. When this arrangement is brought about the springs 77 and 78 will function to absorb the shock normally transmitted to the spade firing mechanism on the counterrecoil of the gun or guns, and thus the side firing

mechanism will become a shock absorber for the rear or spade firing mechanism.

It has been found by actual test over a considerable period of time that the association of the mechanisms which have heretofore been described has resulted in the acceleration of the firing so that the number of rounds per minute has been greatly increased, has resulted in a reduction of the pattern area on the target to a great degree, and, most important, has resulted in continuous firing of twin machine guns for a great number of rounds without "stoppage" of either of the guns.

What is claimed is:

1. In combination, a carriage for twin guns having side firing mechanism, a pair of cradles for said guns, slide means for supporting said guns in said cradles adjacent their rear ends for longitudinal reciprocations, means for pivotally supporting said guns located between their ends for elevation and depression, adapters rigid with said guns forwardly of said pivotal support means and movable longitudinally with said guns, and means located forwardly of said pivotal support means cooperating with said adapters for arresting the movements of said guns in both directions of reciprocation, said last mentioned means including springs for resisting the movement of said guns in each direction in sequential increments.

2. In combination, a carriage for twin guns having side firing mechanism, a pair of cradles for said guns, independent slide means for supporting said guns in said cradles adjacent their rear ends for longitudinal reciprocations, pivotal means for supporting said guns between their ends for elevation and depression, independent adapters rigid with said guns forwardly of said pivotal means and movable longitudinally with said guns, and independent means located forwardly of said pivotal means cooperating with said adapters for arresting the movements of said guns in both directions of reciprocation, said last mentioned means including springs for resisting the movement of said guns in each direction in sequential increments.

3. In combination, a carriage for twin guns having side firing mechanism, a pair of cradles for said guns, slide means for supporting said guns in said cradles adjacent their rear ends for longitudinal reciprocations, means for pivotally supporting said guns located between their ends for elevation and depression, adapters rigid with said guns forwardly of said pivotal support means and movable longitudinally with said guns, means located forwardly of said pivotal support means cooperating with said adapters for arresting the movements of said guns in both directions of

reciprocation, said last mentioned means including springs for resisting the movement of said guns in each direction in sequential increments, and means for adjusting each of said last mentioned means independently of the other.

4. In combination, a carriage for twin guns having side firing mechanism, a pair of cradles for said guns, independent slide means for supporting said guns in said cradles adjacent their rear ends for longitudinal reciprocations, pivotal means for supporting said guns between their ends for elevation and depression, independent adapters rigid with said guns forwardly of said pivotal means and movable longitudinally with said guns, independent means located forwardly of said pivotal means cooperating with said adapters for arresting the movements of said guns in both directions of reciprocation, said last mentioned means including springs for resisting the movement of said guns in each direction in sequential increments, and means for adjusting each of said last mentioned means independently of the other.

5. In combination, a carriage for twin guns having side firing mechanism, a pair of cradles for said guns, slide means for supporting said guns in said cradles adjacent their rear ends for longitudinal reciprocations, pivotal means for supporting said guns between their ends for elevation and depression, and means located forwardly of said pivotal means for arresting the movement of said guns in both directions of reciprocation in increasing increments of resistance.

AUGUST A. DANIELSEN,
ARMAND P. SCHLERET.
